UNITED STATES PATENT OFFICE.

HERSCHEL OLDHAM, OF ESCONDIDO, CALIFORNIA, ASSIGNOR OF TWO-FIFTHS TO F. D. HALL, OF ESCONDIDO, CALIFORNIA.

INTERNAL-COMBUSTION ENGINE.

1,212,100.

Specification of Letters Patent.

Patented Jan. 9, 1917.

Application filed September 24, 1915, Serial No. 52,390. Renewed September 28, 1916. Serial No. 122,738.

To all whom it may concern:

Be it known that I, HERSCHEL OLDHAM, a citizen of the United States, and a resident of Escondido, in the county of San Diego and State of California, have invented a new and Improved Internal-Combustion Engine, of which the following is a full, clear, and exact description.

My invention relates to internal combustion engines of the so called reciprocating-rotary type, that is, to internal combustion engines in which motion is conferred upon a rotor or revoluble member by the action of cylinders containing pistons having a thrusting movement so directed that the pistons turn bodily with the rotor.

The purpose of my invention is to simplify and otherwise improve the mechanism employed and to increase the general efficiency of the same.

Reference is made to the accompanying drawings forming a part of this specification and in which like characters indicate like parts.

Figure 1 is a front elevation showing my improved engine, certain parts being broken away. Fig. 2 is a view somewhat similar to Fig. 1 but with the face plate and some other parts of the engine removed; Fig. 3 is a section on line 3—3, Fig. 1, looking in the direction of the arrow; and Fig. 4 is a detail view, showing in rear elevation the main cam plate.

The base plate 5 is provided with a pair of pedestals 6 and 7 extending upwardly from it and having bearings 8 and 8^a. A revoluble shaft 9 extends through the bearing 8 and is supported thereby. This shaft carries the back plate 10 of the engine. A casing band 11 is mounted upon the back plate 10, and a face plate 12 is secured to the casing band. The back plate 10, casing band 11 and the face plate 12 together constitute a hollow casing which turns bodily with the shaft 9, which serves as the power shaft of the engine. A number of cylinders 13 and 14 are carried by the casing and extend outwardly therefrom. The cylinders 13, in this instance three, are exactly like the cylinders 14, also three in number, but differing therefrom in the cycle taking place within the cylinder at a particular instant, as herein-after explained. Each cylinder is provided with radiating ribs 15 to throw off superfluous heat and thus prevent said heat from

damaging the cylinder. Each cylinder is provided with a piston 16 having a piston rod 17 secured rigidly to it, this piston rod having no swinging movement relatively to the piston but merely a thrust movement inward and outward. Each piston rod 17 carries a head 18 and mounted on the latter is a roller 19.

A cam plate is shown at 20, and because of the function performed by this part I designate it as the main cam plate. It is mounted rigidly upon a sleeve 21, the latter extending through the bearing 8^a and being normally fixed relatively to this bearing. A bolt 53 is used for the purpose of holding the sleeve rigidly in position. The sleeve 21 is hollow and its outer end is closed by a closure plug 22. Extending through this plug and communicating with the interior of the sleeve 21 is a pipe 23 through which explosive mixture is drawn into the sleeve.

The sleeve 21 is further provided with holes 24, and communicating with these holes are a number of supply tubes 25 extending radially outward for the purpose of distributing explosive mixture. The supply tubes 25 communicate with intake chests 26 each having a valve seat 27. Mounted upon each valve seat 27 and movable relatively to the same is a valve 28. This valve is mounted upon a valve stem 29 and is rendered accessible by a closure plug 30, which may be removed for this purpose. The valve stem 29 carries an annular disk or nut 31. A spring 32 engages each disk or nut 31 and encircles a sleeve 33 which extends a slight distance radially inward from the intake chest 26. There are as many intake chests 26 as there are cylinders. I also provide a number of exhaust chests 35 equal to the number of cylinders and intake chests. Each exhaust chest 35 is provided with a valve 36 having a valve stem 37 and being rendered accessible by a closure plug 38, which is disposed in alignment with it and is removable. Each valve stem 37 carries a disk or nut 39, and engaging the latter is a spiral spring 40 which encircles the adjacent portion of the valve stem 37 and also encircles a sleeve 41 which extends radially inward from the exhaust chest. The parts are so arranged that when the valve 36 is moved outwardly from its normal position communication is established between the ex-

haust chest and the outer end of the adjacent cylinder. Each exhaust chest is provided with a short exhaust pipe 34 through which burnt gases can readily escape into the atmosphere. Extending through the wall of the casing are a number of sleeves 42. Extending through each of these sleeves is a dolly rod 43 carrying a nut 44 to facilitate its adjustment relative to the sleeve and to the valve stem 29 which is in alignment with the dolly rod, so that when the dolly rod is moved radially outward it pushes endwise upon the stem 29 and thus raises the valve 28 from its seat 27. There are as many sleeves 42 and dolly rods 43 as there are cylinders.

I also provide a number of sleeves 45 equal to the number of cylinders, each sleeve 45 being similar to the sleeve 42 above described but located a little nearer the face plate 12 than the sleeve 42 just mentioned. Each sleeve 45 carries a dolly rod 47, the latter being provided with a nut 46 and being in exact alignment with the adjacent valve stem 37. Whenever the dolly rod 47 is moved radially outward, that is, when it moves outwardly in the direction of its own length, it bears against the end of the adjacent valve stem 37, and thus moves the valve 36 radially outward. This establishes communication between the exhaust chest 35 and the outer end of the adjacent cylinder 13.

Disposed adjacent the main cam plate 20 and loosely encircling the adjacent end of the sleeve 21 is a revoluble spider 48 provided with wide spokes 48^a, the form of which may be readily understood from Fig. 2. These spokes engage the casing band 11 and thus partially support the casing. Two cam plates 49 and 50, each having approximately a circular form, are secured rigidly upon the sleeve 21. These cam plates, like the main cam plate 20, are normally stationary. The cam plate 49, because of the office it performs, I designate as an intake-controlling cam. The cam 50, in accordance with its function, I designate as an exhaust-controlling cam.

A revoluble collar 51 encircles the stationary sleeve 21 and is secured to the face plate 12 of the casing, which, as above explained, is revoluble. The collar 51 is provided with a hub portion 51^a with which the inner ends of the supply tubes 25 are connected. The hub portion 51^a is provided with a manifold passage 51^b of annular form extending entirely around the sleeve 21 for the purpose of facilitating communication between this sleeve and the supply tubes 25. A packing 52, serving to some extent the purpose of a bearing, is carried by the hub portion 51^a and engages the stationary sleeve 21.

The intake cam plate 49 is provided with a number of lobes 54 equal to one-half the

number of cylinders. In this particular instance therefore there are three of these lobes. The exhaust cam plate 50 is likewise provided with three lobes, which are numbered 55. The main cam plate 20 is provided with a number of groove sections 20^a, 20^b, 20^c and 20^d arranged zigzag so as to assume the form of a six-pointed star, as will be understood from Fig. 4, the groove sections being placed end to end and thus forming a single continuous groove, the general outlines of which correspond to a six-pointed star.

The rollers 19 all extend into this groove. The parts are so arranged and proportioned that whenever the casing and parts carried by it are, as a unit, rotated relatively to the sleeve 21 and cam plates 20, 49 and 50, the various rollers 19 are all first moved radially inward toward the center of the main cam plate 20, and are next all moved radially outward, that is, away from said center. In addition, the parts are so arranged that mere rotation of the casing, no matter from what cause, will have a tendency to move the pistons 16, owing to the fact that the rollers 19 must follow the star-shaped groove.

The arrangement of the various parts is such that three of the cylinders are all performing a given cycle while the three other cylinders are all performing a different cycle. For instance, whenever the cylinders 14 are each engaged in intaking the explosive mixture, the cylinders 13 are each being subjected to the internal combustion of a charge previously inducted and compressed within it. This is a four-cycle engine and is so arranged that each cylinder is subjected to the four cycles conventionally used, namely, intaking, compression, explosion, and exhaust coupled with scavenging. In performing these four cycles each cylinder moves one-third of a revolution, and therefore each cylinder makes three power strokes during one complete revolution of the casing. For instance, if the roller 19 carried by the piston rod 17 of the cylinder 14, shown at the top of Fig. 3, moves obliquely inward, following the groove section 20^a for purposes of intaking, the same roller will move obliquely outward following the groove section 20^b for purposes of compressing; reaching the outer limit of the groove section 20^c explosion will take place in the cylinder in question, and then the roller 19 of this cylinder will travel obliquely inward, following the groove section 20^d. The next successive groove section will take care of the exhausting and scavenging, the process here described being repeated over and over for this cylinder. The action of the other two cylinders numbered 13 is identical with that just described. The three cylinders under discussion act exactly alike and simultaneously as to function. The other three cylinders 18, however, while

undergoing operations similar to those just described, differ therefrom in phase or cycle, as elsewhere explained.

The operation of my device is as follows:

- 5 An explosive mixture being admitted through the pipe 23 into the sleeve 21, portions of this mixture pass radially outward through the supply pipes 25 and into the intake chests 26. Here it remains until the 10 valves 28 are opened, these valves being opened periodically by action of the lobes 54 on the inlet cam. The valves 28 are so timed that the explosive mixture is fed into the cylinders at the precise instant when, owing 15 to inward travel of the piston 16, partial vacuums are created in the outer ends of the cylinders. Then, after compression and explosion, the exhaust valves 36 are opened by action of the lobes 55 carried by the exhaust 20 cam plate 50, the lobes in question actuating the dolly rods 47, and these, as above described, opening the exhaust valves 36.

I do not limit myself to the precise mechanism shown, as variations may be made 25 therefrom without departing from the spirit of my invention.

Having thus described my invention, what I claim as new and desire to secure by Letters Patent is as follows:

- 30 1. In an internal combustion engine, the combination of a support having alined bearings, a sleeve secured in one of said bearings, a casing mounted to turn relative to said sleeve, the sleeve extending through one side of the casing, a power shaft extending through the other bearing of the support and connected rigidly with the other side of said casing, cylinders mounted upon said casing, a piston slidably mounted within each cylinder, a piston rod secured rigidly to said piston, an intake chest disposed adjacent each cylinder and adapted to communicate therewith, an exhaust chest disposed adjacent each cylinder and adapted to communicate with the same, a main cam plate within the casing and rigidly connected with the inner end of said sleeve, the piston rods engaging said main cam plate, an intake-controlling cam plate, and 45 an exhaust-controlling cam plate mounted rigidly upon said sleeve within the casing, means for supplying an explosive mixture to said intake chests, mechanism actuated by the intake cam plate for delivering charges of explosive mixture from the intake chests to said cylinders, and mechanism actuated by said exhaust-controlling cam plate for discharging burnt gases from the said cylinders.
- 50 60 2. In an internal combustion engine, the combination of a support having alined bearings, a sleeve secured in one of said bearings, a main cam plate, an intake-controlling cam plate and an exhaust-controlling cam plate mounted rigidly upon said
- 55 sleeve at one side of the main cam plate, a casing mounted revolubly in relation to said sleeve and inclosing all of said cam plates, the sleeve extending through one side of the casing and carrying the main cam plate 70 at its inner end, a power shaft extending through the other bearing and connected rigidly with the other side of said casing and adapted to be turned by the rotation thereof, cylinders mounted upon said casing, pistons slidably mounted within said cylinders, piston rods connected rigidly with said pistons, heads carried by said piston rods, rollers mounted upon said heads and engaging said main cam plate so as to 75 establish a working relation between said pistons and said main cam plate, mechanism connected with said intake cam plate and actuated thereby for delivering charges of explosive mixture to said cylinders, and 80 other mechanism associated with said exhaust-controlling cam plate and actuated thereby for discharging burnt gases from 85 said cylinders.
3. In an engine, the combination of a 90 revoluble casing, a power shaft connected rigidly with one side of the casing and adapted to receive its power by the rotation of the casing, a plurality of cylinders carried by said casing, pistons slidably 95 mounted within said cylinders, piston rods connected with said pistons, stationary mechanism including a sleeve in line with the shaft and on which the casing is mounted to rotate, and a cam on the inner end 100 of said sleeve engaging said piston rods and co-acting therewith for maintaining a working relation between said stationary mechanism and said revoluble casing, an intake chest and an exhaust chest at one side of 105 each cylinder and adapted to communicate therewith, a valve for controlling communication between said intake chest and the cylinder with which it is associated, a separate valve for controlling communication between each exhaust chest and the cylinder with which it is associated, a valve stem for each valve extending inward from the said chests and having guided movement, a dolly rod for each valve stem, said dolly 110 rod having guided movement in said revoluble casing and being disposed in alignment with the valve stem with which it is associated so that the movement of a dolly rod causes the corresponding valve to open, 115 the dolly rods controlling the inlet valves being disposed in one plane and the dolly rods controlling the exhaust valves being disposed in a different plane, and a pair of cam plates housed within said revoluble casing and located alongside each other, said cam plates being stationary on said sleeve and provided with lobes disposed within the path of travel of said dolly rods.
- 120 65 4. In an internal combustion engine, the 130

combination of a support having alined bearings, a casing, a revolute shaft extending through one of said bearings and rigidly secured to one side wall of the casing, the shaft being rotated by the rotation of the casing, a hollow sleeve rigidly secured in the other bearing and extending through the other side wall of the casing to the interior thereof, a main cam plate rigid on the inner end of the sleeve, cylinders carried by said casing, pistons in said cylinders having piston rods engaging the said cam plate, an intake chest and an exhaust chest at one side of each cylinder, means for supplying explosive mixture to the hollow sleeve, the sleeve having openings, a revolute collar surrounding the said sleeve and secured to the side wall of the casing, the collar having a hub portion, supply tubes communicating with the intake chests and connected at their inner ends to said hub portion, the said hub portion of the collar having an internal annular passage communicating with the openings of the sleeve and the inner ends of said supply tubes, valves for controlling communication between the said intake and exhaust chests and the said cylinders, cam plates mounted rigidly on the said sleeve alongside each other, and means controlled by said cam plates on the rotation of the casing for actuating said valves.

5. In an internal combustion engine, the combination of a support having alined bearings, a casing having a back plate, a casing band mounted on the back plate, and a face plate secured to the casing band, a revolute shaft carrying the back plate and extending through one of said bearings, a hollow sleeve rigidly secured in the other bearing and extending through the face plate to the interior of the casing, a main

cam plate at the inner end of said fixed sleeve, means for supplying explosive mixture to the fixed sleeve, the said sleeve being provided with openings leading therefrom, a plurality of internal combustion cylinders carried by said casing, a piston slidably mounted within each cylinder, piston rods secured to said pistons and provided with means for engaging the main cam plate, an intake chest and an exhaust chest located adjacent each other at one side of each cylinder, supply tubes communicating with the said intake chests, a revolute collar surrounding the said sleeve and secured to the said face plate of the casing, the collar having a hub portion to which the inner ends of the supply tubes are connected, the hub having an annular passage communicating with the inner ends of the supply tubes and with the openings of the said fixed sleeve, valves for controlling the communication between the intake chests and the adjacent cylinders, valves for controlling the communication between the cylinders and the exhaust chests, an intake cam plate and an exhaust cam plate secured rigidly upon the said fixed sleeve adjacent each other and between the said main cam plate and the face plate of the casing, and means controlled by said cam plates on the rotation of the casing for actuating said valves to admit charges of explosive mixture from said intake chests into the adjacent cylinders and to discharge burnt gases from said cylinders.

In testimony whereof I have signed my name to this specification in the presence of two subscribing witnesses.

HERSCHEL OLDHAM.
